UNITED STATES PATENT OFFICE.

FREDERIC L. WANKLYN, OF MONTREAL, QUEBEC, CANADA.

RAILWAY-TRACK TORPEDO.

Application filed June 8, 1921. Serial No. 476,043.

To all whom it may concern:

Be it known that I, FREDERIC L. WANKLYN, of the city of Montreal, Province of Quebec, Dominion of Canada, a subject of 5 the King of Great Britain, have invented a new and useful Improvement in Railway-Track Torpedoes; and I do hereby declare that the following is a full, clear, and exact description thereof.

10 My invention relates particularly to torpedoes for use along the railway track as signals for approaching trains and has particular reference to torpedoes made from non-metallic material. The object of the

15 invention is to provide a more efficient torpedo of simple construction and one which will embody in itself a property for expediting the explosion.

To this end the invention may be said to 20 consist of a base having a shaped top, preferably molded, the margin of which and the corresponding margin of the base, after the torpedo has been charged, are treated with a suitable substance to cause these contacting portions to be sealed preferably by merging or adhering and thus produce an integral structure absolutely waterproof in all respects. The material I prefer to use is a specially treated celluloid to be sealed 25 preferably by merging or adhering, known to the trade as pyralin and the sealing substance is preferably acetone or a suitable cementing compound. In addition to the waterproof nature of pyralin and its capacity for being united one piece to another 30 by merging, it is highly inflammable and augments the burning of the detonator and consequently expedites the explosion. This container is fastened to a resilient spring 35 clip of metal or other substance having like properties preferably by a pyralin strip *m* and an iron rivet *p* both of which secure the clip to the underside of the container.

The container may be protected, if desired, by a covering of suitable waterproofing or heat resisting material, or both, such as asbestos cement or other substance having a like function.

For full comprehension, however, of my 50 invention reference must be had to the accompanying drawings in which similar reference characters indicate the same parts and wherein:

Figure 1 is a plan view of a torpedo constructed according to my invention;

Figure 2 is a side elevation thereof;
Figure 3 is an end elevation thereof;
Figure 4 is a sectional view taken on line 4-4 Figure 3;

Figure 5 is a plan view of the blank for 60 forming the base of the container.

Figure 6 is a plan view of the blank for 65 forming the top of the container;

Figure 7 is a sectional view of the top and 70 the base of the container;

Figure 8 is a detail view of the pyralin 75 strip for securing the spring clip to the container;

Figure 9 is a detail view of the rivet for 80 securing the clip to the container; and

Figure 10 is a detail view of the clip.

In the embodiment of my invention illustrated the base *b* is cut to size from a sheet of pyralin or other celluloid and pyroxylin plastic material, and the top or cover is also 85 cut from the same material and of the same general shape as the base but sufficiently larger to have the same size when it is molded to the shape *d* or any other shape suitable to form a receptacle for the detonator *e* and flashlight powder *f*. Thus formed it presents a surrounding flange *g* adapted to fit upon the margin of the base *b*. The material pyralin, because of its celluloid content, lends itself readily to the merging 90 of the flange of the top *d* with the margin of the base by the use of acetone as a solvent. The spring clip for securing the torpedo upon the rail head is indicated at *k* and preferably consists of a unitary length of 95 flat spring metal bent to inverted U-form with turned in ends which engage the underside of the rail head. The middle portion of this clip is secured to the underside of the container in a position disposed transversely thereto by a strip of pyralin *m* and a rivet *p*, the strip having openings *n* to permit the passage of the clip therethrough.

The parts are assembled by first attaching the base *b* to the clip by the fastening piece 100 *m*, the latter being merged to the underside of the base by smearing the contacting face with acetone and then pressing them together. After the base and clip have been fastened together the torpedo is charged and the contacting faces of the flange of the top and the margin are smeared with acetone and are then pressed together. The entire container is then coated with asbestos cement or other fire-resisting and durable sub- 110

tances suitable to reinforce the container and at the same time render it fireproof.

The inflammable nature of the container with its fire-resisting coating imparts to the 5 torpedo an important advantage in that the burning of the detonator and flash light powder are augmented and consequently the explosion expedited.

If desired the shape of the container illustrated may be changed, and other reinforcement substance employed without departing 10 from the spirit of my invention.

What I claim is as follows:

1. In a torpedo of the type described, a 15 container of a material of the class celluloid and pyroxylin plastic and a fire resisting coating completely covering the container.

2. In a torpedo of the type described, a 20 container consisting of pyralin with a protecting coating completely covering the same.

3. In a torpedo of the type described, a container consisting of a base and a cham-

bered top or cover, said base and top being 25 merged together.

4. In a torpedo of the type described, a 30 container consisting of a pyralin base and a chambered pyralin top or cover said base and top being merged together.

5. A container for a railway track torpedo consisting of a flat base, a top comprising a hollow convex portion and a flat 35 outwardly projecting flange surrounding said portion and formed integrally therewith, said flange being merged with the margin of the base.

6. A container for a railway track torpedo, consisting of a flat pyralin base, and 40 a convex pyralin top having a flange merged with the margin of the base.

In testimony whereof I have signed my name to this specification in the presence of two witnesses.

FREDERIC L. WANKLYN.
